UNITED STATES PATENT OFFICE.

WILLIAM CHASE, JR., OF INDIANAPOLIS, INDIANA.

CIRCULAR-GLASS CUTTER.

959,311.

Specification of Letters Patent. Patented May 24, 1910.

Application filed July 1, 1909. Serial No. 505,349.

To all whom it may concern:

Be it known that I, WILLIAM CHASE, Jr., a citizen of the United States, and a resident of Indianapolis, in the county of Marion 5 and State of Indiana, have invented a new and Improved Circular-Glass Cutter, of which the following is a full, clear, and exact description.

Among the principal objects which this 10 invention has in view are to provide an implement which may be centrally located upon the surface of glass and there immovably held, and to provide a swinging arm pivotally mounted upon a fixed structure and 15 hingedly secured thereto.

Reference is to be had to the accompanying drawings forming a part of this specification, in which similar characters of reference indicate corresponding parts in all the 20 views.

Figure 1 is a perspective view of a glass cutter constructed in accordance with the present invention; Fig. 2 is a vertical section of the same, showing the extension rod in 25 full lines; and Fig. 3 is a cross-section taken on the line 3—3 in Fig. 2.

The extension rod 4 is partly circular in cross-section and is provided with a flattened upper surface 5 which forms a guide 30 for the head 6. On the rounded surface of the rod 4 are provided scale markings 7 by which the head is placed on the said rod. The head 6 is provided with a depending bifurcated extension 8 adapted to carry a rotary cutting wheel 9. Extended from the upper surface of the head 6 is a screw-threaded extension 10 adapted to engage the screw-threaded nut 11. The head 6 is perforated, as shown at Fig. 3 of the drawings, 40 to snugly fit the extension rod 4. It is upon the flattened or square surface 5 of the extension rod 4 that the rubber washer 12 is seated when the nut 11 is screwed up on the extension 10.

45 The washer 12 being constructed of a suitable material, the head 6 is held in the position to which it is adjusted before the nut 11 is tightened. This adjustment is aided by means of the scale 7. This scale is constructed with reference to the center of the pivot on which the rod 4 swings, that is, the first marking of the scale from the pivot is the marking to represent the number of inches or fractions thereof at which the said 55 marking is removed from the pivot.

The pivot consists of a tubular extension

set up from a circular plate 13. The tubular extension is provided with a converged end 14, between which and the body of the extension there is formed a groove 15 provided 60 to receive the ring 16, surrounding an opening in the rubber bulb 17. The tubular extension is further provided with a central opening 18 communicating from the inside of the bulb 17 and with a chamber formed 65 under the plate 13 by the flange 19 and the rubber gasket 20. The flange 19 is of slightly less diameter than the plate 13, forming thereby a rabbeted edge to receive the gasket 20. The gasket 20 is constructed 70 of suitable rubber, that most preferred being soft in texture, and is adapted to conform to the surface of the glass and to form an air-tight joint therewith.

The tubular extension is grooved at 21 to 75 receive a pin 22 which is driven tangentially across the opening in a collar 23 to form a lock pin to hold the said collar in rotary position upon the said extension. The pin 22 is elongated to extend beyond the collar 80 23 to form the hinge pivots for the hinge end 24. The collar 23 is flattened on the two opposite sides, as at 25, to accommodate the hinged extensions 26 of the hinge end 24 and thereby provide guides for the hinge 85 swing of the hinged end 24 and the extension rod 4 to which it is secured by the threaded extension 27 of the said rod 4. At the rear end of the said loop the surface 28 is extended to pivot 22 of the hinged end 24 and 90 the rod 4 connected therewith.

Having an implement constructed as shown and described, the operation thereof is as follows: Having located the center from which the cutting is desired, the plate 95 13 is placed in position concentrically therewith. The bulb 17 is compressed to eject the air therefrom when the gasket 20 by means of the plate 13 is pressed firmly against the glass while the bulb 17 is released. The bulb 17 is constructed of strong 100 resilient walls adapted to resume their spherical shape, rarefying the air contained within the said bulb and the chamber formed below the plate 13, forming a strong 105 and persistent suction. This suction secures the pivot extension firmly in position. The head 6 is now adjusted to the desired cut, and when so adjusted the screw 11 is tightened to set the washer 12 hard down on the 110 flat extension 5 of the rod 4. The head 6, carrying the cutter 9, is now in position for

operation. This is accomplished by lowering the cutter upon the surface of the glass and bearing upon the rod sufficiently to embed the cutting point in the glass as the 5 rod is swept around the pivot center of the extension on the plate 13. When the circular cut is formed as desired, the instrument is released from its hold on the glass by compressing the bulb 17, which relieves 10 the rarefaction in the chamber under the plate 13 and releases the same and overcomes the air suction produced by the above-described operation.

Having thus described my invention, I 15 claim as new and desire to secure by Letters Patent:

1. A circular glass cutter comprising a fixed metal plate having a depending yielding continuous flange and a vertical extension 20 adapted to form a pivot for a swinging arm, said extension being perforated to form communication with the under side of the said plate, means for extracting the air from under said plate to cause a partial 25 vacuum thereunder, and an extension arm pivotally connected with said vertical extension and carrying a cutting instrument adapted to cut glass.

2. A circular glass cutter comprising a 30 metal plate having a continuous yielding depending flange adapted to form a chamber under said plate in conjunction with the glass to be cut, said plate having a vertical extension provided with a tubular perforation opening outward from said chamber formed by said flange, a collar surrounding 35 said vertical extension, an extension rod hingedly connected to said collar, a cutting device slidably mounted upon said rod, and 40 means for rarefying the air below said plate to form a suction to seat the said yielding flange upon the said glass.

3. A circular glass cutter comprising a 45 plate having a continuous yielding depending flange adapted to form a chamber below the said plate in conjunction with the glass to be cut, said plate having a tubular extension provided with a perforation leading outward from said chamber, a collar pivot-

ally mounted upon said vertical extension, 50 a rod hingedly connected with said collar, a cutting instrument slidably mounted upon said rod, and a resilient compressible bulb adapted to fit over the said vertical extension to be compressed to displace the air in 55 said chamber, and expanded to rarefy the remaining air in said chamber.

4. A circular glass cutter comprising a plate having a rubber gasket depending from said plate to form a chamber below the 60 same, said plate having a tubular extension forming an air passage outward from said chamber, a collar pivotally mounted upon said extension, an extension rod hingedly connected to said collar and provided with 65 scale markings, a cutting instrument slidably mounted upon said rod, means for holding the said cutting instrument fixedly in position on said rod, and a compressible rubber bulb adapted to extend over said extension and adapted by a compression and expansion thereof to form a rarefaction of the same in said chamber under said plate.

5. A circular glass cutter comprising a 75 plate having a continuous rubber gasket depending therefrom to form a chamber beneath the said plate in conjunction with the glass to be cut, a vertical tube mounted upon said plate and forming open communication with the chamber below the same, said tube 80 having a groove at the upper end to receive and hold a compression bulb, a collar pivotally mounted upon said tube, an extension rod hingedly connected to said collar, a cutting implement adapted to slide longitudinally on said rod, means for maintaining 85 said cutting implement in a vertical position, and a collapsible rubber bulb adapted to extract the air from the chamber formed under the said plate and within the said 90 rubber gasket.

In testimony whereof I have signed my name to this specification in the presence of two subscribing witnesses.

WILLIAM CHASE, JR.
